METHOD OF CONNECTING PARTS.

Application filed January 12, 1924. Serial No. 685,829.

My invention pertains to a method of connecting parts and more particularly to the art of attaching a pair of metal members by causing one to project through an opening in the other so as to permit of an infinitesimal pivotal action while supplying adequate reinforcement. One part may be called the perforated member and the other part the intersecting member. More specifically, the several features to be optionally combined are:—

1. The fashioning of an edge portion which defines the opening in the desirably thin perforated member as a curved surface which merges with one side of the perforated member to facilitate achievement of a precise fit with a filleted portion of the intersecting member which is to have a complementarily designed surface defined by a curve disclosed by a longitudinal section of the intersecting member.
2. The tubular formation of the intersecting member.
3. The provision around the opening in the perforated member of a reinforcing flange.
4. The expansion of the inserted end of the intersecting member.

5. The spinning-over of the extremity of the intersecting member against or even around the flange so that, as the extremity becomes progressively expanded, the intersecting member will be drawn lengthwise in a direction through the opening until the fillet becomes seated with circumferential uniformity and as a universally rockable fit against the curved surface.

6. The projection of the hole-bordering flange from the side of said perforated member opposite to that side of it with which said curved surface merges.

The drawings exemplify the adoption of the principles of my invention for the manufacture of a spoke and felloe connection.

45 This application is a continuation in part of my copending applications Serial No. 479,787, filed June 23, 1921, and Serial No. 631,328, filed April 11, 1923.

The stresses to which a spoke and felloe connection is subjected during the road service of a wheel are changing and severe. If they are localized to too small a surface contact between the spoke and felloe they cannot be adequately resisted and success-

fully withstood. When a wheel rotates under load the points of connection between the spokes and felloe become subjected to very severe stresses of a compound character, often comprising sway in changing directions at angles to any particular radius of the wheel or to some particular spoke axis. That is a sort of pivotal action. Moreover, the rims of wheels are frequently violently shoved laterally away from the circular plane of the wheel. Such action corresponds to what is known in the laboratory as the cantilever test.

I solved a problem by producing a very slightly yielding hollow spoke and felloe connection so nicely fitted with circumferential uniformity as successfully to combine sufficient strength with a minimum of weight. In order to best effect a uniformity of fit or equalization of strength around each spoke and felloe connection a spinning operation is employed in a new way. It was important to have realized that a uniformity of contact or fit over a curved filleted surface was essential to produce reliable results, and to perceive the method by which such a uniformity of fit might be obtained. The spinning operation for expanding over the extremity of a hollow spoke so that, when the nave end of the spoke is properly supported, the spoke is necessarily drawn outwardly through the felloe hole and so that the outer fillet surface of the end of the spoke is drawn so uniformly against a curved surface defining the inner end of a felloe opening through which it projects as to make it absolutely conform thereto is a feature which stands forth as one outstanding improvement. Neither upsetting nor peening can reliably insure so perfect a conformity of fit. Another feature of my invention is the provision of a reinforcing flange around the felloe opening and preferably an outwardly projecting flange against which the outer spoke end may be expanded or over the extremity of which the outer end of the spoke is to be spun over and curled. A comparatively large area of contact between surfaces defined by parallel section lines which recede from the spoke axis as provided by my invention inherently affords a desirable infinitesimal flexibility when the wheel rotates in use, to afford what may be termed a rolling bearing

affording universal pivotal movement along the curved surface contact. The felloe flange reinforces and permits of minimizing the thickness of the felloe and therefore of realizing reduction in weight. My connection resists the stresses by having the spun over flange of a load sustaining spoke press up the felloe flange toward the wheel center which felloe flange in turn presses upwardly against the inclined shoulder or fillet of the spoke thereby distributing both load and impact with an easing effect.

The practically tested felloe and hollow spoke connections of the prior art have been proven to have been insufficiently strong whether welded or not. A welded spoke and felloe connection, because of the likelihood of fracture of the integral union and with consideration of the light weight demanded by the trade or minimization of mass along the felloe, has been generally condemned. I have also learned that a flat surface contact between a tubular spoke protuberance and felloe is to be avoided because likely closely to localize stresses rather than to distribute them as does my curved surface contact over a much larger area which is mainly oblique with reference to a particular spoke axis. If after the spoke is inserted through the felloe the outer end of the spoke be punch upset differing portions of the opposed surfaces of the spoke and felloe are necessarily forced apart. Therein lay another fault which contributed to the commercial failure of such construction, because if the opposed surfaces do not reliably conform and completely contact the stresses will not be uniformly distributed and looseness and eventual fracture will occur.

The subject matter of this application declares these distinct improvements some of which are solely novel and some in cooperative combination with others (a) fitting a spoke fillet against a flared felloe-hole-defining surface of considerable area (b) fitting the felloe-inserted end of the spoke within an outwardly projecting felloe-hole-bordering flange of considerable area, (c) making a spun over connection with its resulting accurate and therefore reliable curved surface fit, (d) spinning over to interlock the end of a tube, (e) spinning a tube end over a hole-bordering flange and (f) spinning and curling the end of a tubular spoke over a reinforcing felloe-hole-bordering flange.

The inventive conception is embodied in steps which are hereinafter explained and variously combined in the claims, while the annexed drawing and particular description thereof together set forth in detail modified forms constituting my invention, the disclosed means, however, being but some of various mechanical combinations in

which the principle of my invention may be applied.

Referring to the drawings:

Figure I is a fragmentary front elevation of an assembled wheel showing a felloe and spokes having outer ends inserted through outwardly flanged holes therein some before and some after being spun over, together with apparatus for effecting the interlocking spoke and felloe connection.

Figure II is a side elevation of the parts shown in Figure I with certain concealed portions shown in dotted lines and with others shown in section.

Figure III is a view on line III—III of either Figure I or II.

Figure IV is an enlarged fragmentary sectional view of a felloe opening and spoke end initially projected therethrough together with a suitable spinning tool in position preparatory to its use.

Figures V to VIII inclusive are views similar to Figure IV showing successive stages which may be adopted for performing the spinning operation.

Figures IX to XII inclusive are enlarged sections of various modifications of the spoke and felloe connection effected according to my novel method.

I have shown on the first sheet of the drawings three adequate views of portions of a machine adapted to perform my method. Inasmuch as nothing is herein claimed for the structure of the machine only enough of it has been shown to enable a person skilled in the art to understand its operation and consonantly its structure will be rather briefly described.

A standard 1 carries a stub shaft 2 surrounded at its connected end by a shoulder 3. The shaft 2 is adapted to have mounted upon it the hub 4 of a partly assembled all metal wheel including tubular spokes 5 having abutting nave ends 6 and outer ends 7 of relatively reduced size by reason of the provision of fillets or annular shoulders 8 the surfaces of which are additionally defined longitudinally by a curve, which are defined by a curved surface lying in a longitudinal plane of the spoke and adapted to engage a curved felloe-hole-defining surface 9 when the ends 7 are projected through the circumferentially arranged holes in the felloe 10. As shown in Figures I to VIII inclusive each felloe hole is further defined by an outwardly projecting flange 11. The preliminary steps of my method are the provision near the outer ends of tubular spokes of tapered fillets, the provision of flanged felloe openings and the rounding of the inner portions of the felloe-hole-defining surfaces so that when the outer spoke ends are projected through the felloe openings the curved surfaces of the fillets may snugly engage the curved hole-defining surfaces. The re-

duced outer ends of the spokes should, in order to obtain the preferred product, be long enough to project some distance outwardly beyond the outer rim of the holes or 5 edges of the felloe flanges 11.

The felloe and spokes being assembled and with the nave end of the spokes held in position in any suitable manner, but with the spoke and felloe connections not yet interlocked, the wheel is slipped on to the shaft 2 until one end of its hub 4 abuts the shoulder 3. Each outer spoke end may be separately spun over around the outer edge of a felloe flange 11, but during such operation 10 the particular spoke operated upon should be firmly held in proper position. For this purpose, the standard 1 has projecting from it some distance above the shaft 2 a pair of hollow brackets 12 in which are 15 slidably mounted for up and down movement a pair of wedges 13 which are fashioned with opposed beveled surfaces 14 adapted, when moved upwardly, to engage complementarily beveled surfaces 15 on a 20 pair of spoke clamping jaws 16. Attention is directed to Figure III where it will be seen that the opposed faces of the jaws 16 are fashioned with grooves 17 designed to 25 conform to the curvature of the spoke just beyond its fillet. The jaws 16 are pivotally mounted at 18 and 19 respectively and their opposed grooves are normally held apart by the action of a spring 20. Rods 21 are 30 adjustably connected at 22 one with each 35 of the lower ends of the wedges 13 and the lower ends of the rods 21 articulate at 23 with one end of a lever 24 which is pivoted at 25 to an upstanding arm 26 which may be a part of the standard 1. The other end 40 of the lever 24 is fashioned as a pedal 27 which when depressed by the foot of the operator moves the rods 21 and hence the wedges 13 upwardly to constrict the jaws 16 against opposite sides of a spoke and in 45 opposition to the action of the spring 20. The adjustment afforded at 22 permits of reliably centering the action of the wedges 13 so that the clamping action of the jaws 16 may be uniform whereby to establish the 50 axis of the particular spoke in a predetermined position.

The standard 1 is also provided at its upper end with a bearing 28 in which is rotatably and slidably mounted a hollow 55 spindle 29 to be driven in any desired manner, not shown. Movable mounted in the lower end of the spindle 29 and adapted for sliding movement in a crosswise direction is a slide 30 carrying a depending spinning tool 31 which projects beyond the lower end of the spindle 29. The formation of the spinning tool 31 is more clearly shown on sheet 2 to comprise a central projection 32 which may be fitted to the interior of the 60 outer spoke ends 7 and an annular groove

33 adjacent the projection 32 whereby an annular lesser projection 34 is provided. The width of the annular groove 33 should only very slightly exceed the combined thickness of the felloe flange 11 plus twice the 70 thickness of the tubular stock of the outer end 7 for a reason to be presently manifested.

The spindle 29 is fashioned with an annular groove 35 in which are seated a pair 75 of diametrically opposite blocks 36 connected by means of pins 37 with a lever 38 having its one end pivoted to the standard 1 at 39. The purpose of the lever 38 is to slide the spindle 29 downwardly against the 80 action of a return spring 40 and it may be held in an intermediary position by shoving it laterally so that it is caused to occupy a notch 41 in a bracket 42 which may conveniently depend from the bearing 28. As 85

The slide 30 is provided interiorly of the spindle 29 with an upward projection 43 presenting on the side which is opposed to the center of the spindle a sloping surface 44 as may be clearly seen in Figure II. The slide 30 is normally held in a position in which the tool 31 is concentric with the spindle 29 and incidently so that the axes of the spindle 29, tool 31 and the particular spoke to be operated upon all coincide; by means of a spring 45 which acts to move the slide 30 against an adjustable stop 46. Also mounted within the spindle 29 for coaxial reciprocation relatively thereto is a cone 47 provided with an upwardly extending shank 48. A pin 49 passes through a slot 50 in the spindle 29 and through a grooved collar 51 which loosely surrounds the spindle 29 so that movement to be imparted to the collar will simultaneously cause the movement of the cone 47. A 100

lever 52 is, like the lever 38, pivotally connected with the standard 1 and with the collar 51 and is to be actuated downwardly against the action of a spring 53 to cause the cone 47 to engage the sloping surface of the upward projection 43 and move it laterally against the action of the spring 45 whereby to impart an eccentric movement to the tool 31. An initial stage of such a lateral tool displacement or tool eccentricity is shown in Figures II and V. 110

115 My method is practiced according to the following description:

120 After the preliminary formation of the outer spoke ends and flanged felloe holes and the insertion of the spoke ends through the holes, the nave ends of the spokes are secured in any desired manner to a hub and then the partly assembled wheel is mounted on the shaft 2 and one of the spokes brought to an upright position and firmly held in a posi- 125 130

tion where its own axis coincides with the axes of the spindle 29 and of the tool 31 when in its normal concentric position. This is accomplished by a depression of the 5 foot pedal 27. While the particular spoke, which is to have its outer end spun over, is clamped so as to hold it in proper position, the upper lever 38 is moved downwardly 10 partway and held in the notch 41 in which position the spindle 29 will have moved down just enough to introduce the central 15 projection 32 of the tool into the outer spoke end 7 and so that the lower surface of the projection 32 is elevated with respect to the 20 edge of the felloe flange 11 a distance approximately corresponding with the thickness of the outer spoke end material and as is revealed by the position of the tool 31 in Figure V. The same figure shows the commencement of the spinning-over operation. 25 The lever 38 having been locked in the notch 41, and while the foot pedal 27 is still being held down, the operator commences gradually to pull down on the lever 52 to progressively move the slide 30 and hence the tool 31 to an eccentric position which will therefore necessarily cause so much of the outer 30 spoke end 7 as projects beyond the flange 11 to become progressively and uniformly expanded and to act to draw the fillet 8 firmly against the surface 9, indeed, to effect a circumferential uniformity of fit over the entire abutting surfaces of the outer spoke 35 end and felloe flange. The initial expansion of the outer spoke end causes a slight flare designated by the numeral 54 in Figure V. A continued downward movement of the lever 52 eventually moves the tool 31 far enough aside or to the position in which it 40 is shown in Figure VI until the outer spoke end has been spun as a flange 55 extending across the edge of the felloe flange 11. Then the lever 52 is released and when the cone 45 47 is lifted in response to the action of the spring 53, the spring 45 is permitted to exercise its function of returning the slide 30 to a position in which it engages the stop 46 and so that the tool 31 is again brought to its concentric position as shown in Figure 50 VII. Finally, the lever 38 is withdrawn from the notch 41 and a continuation of its downward movement accomplished whereby to draw down the spindle 29 and hence the 55 spinning tool 31 to the position in which it is shown in Figure VIII whereby the flange 55 is bent down and spun around the edge of the felloe flange 11 so as entirely to enclose it and so as to assume the shape designated as 56 in Figure VIII. Thereafter, the 60 lever 38 is released and likewise the pressure upon the pedal 37, the springs 40 and 20 successively restoring the parts to their original position, which is to say, lifting the tool 31 to the position in which it is shown in Figure 65 IV and effecting a separating movement

of the clamping jaws 16 to release the spoke and permit the operator with a partial rotation of the wheel to bring another spoke into upright position.

In Figure IX is shown a felloe 57 having an opening fashioned with a somewhat curved defining flange 58 and a spoke 59 having a fillet 60 seated against the curled surface 61 of the flange and merely spun at 62 against the flange. A reinforcing plug, in this instance a hollow thimble 63, is then inserted in the spun over outer spoke end to be in turn spun over against the spun over spoke end at 64.

Figure X shows a felloe 65 fashioned with an inwardly projecting hole-defining flange 66 having likewise a curved interior surface 67 to which the surface of a fillet 68, of a spoke 69 conforms when spun over at 70 according to my method. Here also, a thimble 71 may be optionally inserted and have its open end 72 in turn spun over the spun over spoke end.

Figure XI discloses a felloe 73 provided with an opening not reenforced by any kind of a flange though defined by a curved surface 74 against which a complementarily curved surface 75 of a protuberance or bead 76 on a spoke 77 may be precisely seated when the outer end 78 of the spoke is spun over against the outer side of the felloe by reason of the spinning action having acted to draw the fillet surface 75 snugly against the surface 74.

Figure XII discloses a felloe 79 provided with an opening defined by an outwardly projecting flaring or funnel shaped flange 80. A spoke 81 fashioned with a fillet 82 has its outer end 83 uniformly spun against the flange 80 so as to effect the precision of fit which the spinning operation insures.

I claim:

1. The method of securing a progressively smaller outer end portion of a hollow metal member in an opening of another member, which comprises, passing one end of said hollow member through said opening so as to cause it to project beyond the rim of said opening and then spinning the projecting extremity of said hollow member across the rim of said opening to progressively draw said outer end to a wedge fit in said opening and to press said extremity against the area bordering said opening thereby interlocking the parts for infinitesimal universal pivotal motion.

2. The method of securing a filleted outer end of a tubular metal spoke in an outwardly flanged opening of a felloe, which comprises, passing the outer end of the spoke into the flanged opening in the felloe and then expanding the outer spoke end into contact with said flange.

3. The method of securing the open outer end of a hollow spoke, formed near said end

- with a tapered fillet, in a flanged opening of a felloe; which comprises, passing the outer end of said spoke through the felloe opening so as to cause it to project beyond the outer rim thereof and then spinning the projecting end of said spoke to expand it laterally across the rim of said opening to progressively draw said fillet to a wedge fit in the felloe opening.
10. 4. The method of securing the outer ends of a taper filleted hollow metal spoke in a widely flared opening of a felloe, which comprises, passing the spoke through the opening in the felloe until its fillet abuts the area defining said opening, and then expanding the metal of the spoke against the edge of the opening, also against the side of the felloe opposite to the one which the fillet abuts and simultaneously drawing the tapered spoke fillet to its seat.
5. The method of securing a tubular outer end of a spoke fashioned near said end with an annular fillet of progressively decreasing diameter toward the outer end of the spoke, in an outwardly flanged round felloe opening of progressively increasing size toward its inner end until its defining surface merges with the concave side of the felloe and conforms to said fillet surface; which comprises, passing the outer end of said spoke through the felloe hole so as to cause its extremity to project beyond the edge of the defining flange thereof and then causing the extremity of said spoke at a point beyond said fillet to be spun around said flange by effecting a relative rotational movement between said spoke and felloe to progressively draw said fillet to a snug fit.
6. The method of securing the reduced outer end of a hollow metal spoke in an outwardly flanged opening of a felloe; which comprises, inserting the reduced end of the spoke through the flanged opening and then spinning the metal at the outer end of the spoke about the edge of the flange to draw the shoulder formed by the reduced portion tightly against the felloe.
7. The method of making a wheel, which consists, in providing tubular metal spokes each with a tapered fillet and an annular felloe with circumferentially arranged openings each defined by a flared surface conforming to the surfaces of said fillets and merging with the concave side of the felloe, inserting the outer ends of the spokes through said openings respectively until their fillets seat against the hole-defining surfaces, firmly holding the nave ends of the spokes in equispaced radial position, expanding the inserted ends of said spokes while holding one of the parts fixed to bring said fillets and surfaces in wedge fit engagement and then securing the nave ends of the spokes to a hub.
8. The method of securing the outer end of a taper-shouldered hollow metal spoke in the round opening of a felloe; which comprises, passing the spoke through the opening in the felloe until its shoulder abuts the edge of the opening on one side of the felloe, and then spinning the metal of the spoke against the opposite side of the opening to draw the shoulder toward, and seat it with circumferential uniformity against, the felloe.
9. The method of securing the outer end of a tubular spoke, provided near its outer end with a fillet exteriorly defined by an annular concave surface, in an outwardly flanged round opening in a felloe which opening is defined at its inner end by a flared convex surface adapted to conform to said concave fillet surface, which comprises projecting the open outer end of said spoke through said opening, and then expanding the outer extremity of said spoke against said flange so as simultaneously to draw said fillet with circumferential uniformity to a wedge fit against said flared surface.
10. The method of securing the outer end of a tubular spoke, provided near its outer end with an annular fillet surface additionally defined by concentric curves lying in longitudinal planes of the spoke, in a radially extending round opening in an annular felloe which opening has an inwardly flared annular edge surface; which comprises projecting said outer spoke end into said opening and then causing the outer extremity of said spoke to be spun-enlarged against the outer side of said felloe whereby to draw said fillet surface against said flared surface with circumferential uniformity.
11. The method of securing the outer end of a tubular spoke, provided near its outer end with a shoulder defined by a filleted surface surrounding the axis of the spoke, in a radially extending outwardly flanged opening in an annular felloe; which comprises inserting said outer spoke end into said felloe opening and then modifying the inserted end of said spoke whereby to interlock the parts.
12. The method of securing the open outer end of a taper-shouldered hollow metal spoke in the substantially round flange-defined opening of a felloe; which comprises, passing the spoke through the opening in the felloe until its shoulder seats against the edge of the opening at the inside of the felloe, and then spreading the metal of the open outer end of the spoke against the extremity of the flange whereby to interlock the connection.
- Signed by me, this 2nd day of January, 1924.

HERALD P. ARNT.
